(57) CLAIM

(21) Appl. No.: 29/157,381

I claim the ornamental design for a cloth bottle cover with a sheep design, as shown and described.

(22) Filed: Mar. 15, 2002

DESCRIPTION

(51) LOC (7) Cl. 07-06

FIG. 1 shows a front isometric view of one configuration of the sheep cloth bottle cover according to the invention.

(52) U.S. Cl. D7/625; D2/831

FIG. 2 is a front view of the sheep cloth bottle cover according to the invention.

(58) Field of Search D7/624, 625; D9/444; D2/828, 830–832, 839, 741, 719, 725, 745, 746; 428/7, 35.7, 35.8, 36.1, 36.5

FIG. 3 is a back view of a sheep cloth bottle cover according to the invention.

(56) References Cited

FIG. 4 is a left side view of a sheep cloth bottle cover according to the invention.
